(57) **CLAIM**

The ornamental design for an eye protection device for use with eyeglasses, as shown and described.

DESCRIPTION

FIG. 1 is a front elevational view of an eye protection device for use with eyeglasses showing my new design;
FIG. 2 is a rear elevational view thereof with the area shown in broken lines is not part of my new design;
FIG. 3 is a left side elevational view thereof;
FIG. 4 is a right side elevational view thereof;
FIG. 5 is a bottom plan view thereof;
FIG. 6 is a top plan view thereof;
FIG. 7 is a rear perspective view with the area shown in broken lines is not part of my new design; and,
FIG. 8 is a front perspective view with shading on areas that are not part of my new design.
